UNITED STATES PATENT OFFICE.

ARTHUR WARREN MACVEY, OF BROOKLYN, NEW YORK.

AUTOMATIC MUSICAL INSTRUMENT.

1,250,606.

Specification of Letters Patent. Patented Dec. 18, 1917.

Application filed January 28, 1915. Serial No. 4,819.

To all whom it may concern:

Be it known that I, ARTHUR WARREN MACVEY, a citizen of the United States, and a resident of Brooklyn, in the county 5 of Kings and State of New York, have invented certain new and useful Improvements in Automatic Musical Instruments, of which the following is a specification.

The invention pertains more particularly 10 to a novel construction of tracker bar, and the purpose of the invention is to so arrange the air channels in said bar as to eliminate, as far as possible, the mechanical precision of the tones of a player piano.

15 One of the greatest objections to player pianos is the effect produced upon an audience by the absolute precision or mechanical accuracy with which the hammers of the piano act, the result being that instead of 20 the rendition being natural, as though the piano were played by hand, the whole effect is one of mechanism and conveying the impression of mechanically produced music.

In all player pianos known to me the 25 tracker bar channels have been in straight lines, either one or a plural number being employed, and the perforations in the traveling music sheet have been arranged to coöperate with these channels with the 30 utmost mechanical precision, the result being that in the use of the player piano, the notes are struck or the tones sounded with such mechanical accuracy as to produce an unnatural impression and to rob the music 35 of the character which is imparted to renditions thereof by expert musicians playing by hand.

In the playing of pianos even by the most 40 expert musicians slight variations or irregularity in time take place and every audience has become accustomed to music rendered with these slight variations in time, the natural habit of musicians, although very expert, disclosing their inability to 45 strike the notes with that mechanical accuracy which results in the use of a mechanically operated piano. Audiences and individuals having become educated to the playing of pianos by hand naturally, if of an 50 artistic temperament, find limited satisfaction from the music rendered by a player piano.

It is one of the purposes of my invention 55 to so construct the tracker bar of a player piano that the music rendered by the piano shall imitate to as great an extent as possible

hand playing, and in attaining this result I so arrange the air channels in the tracker bar as to produce those slight variations or irregularity in time that are indicative of 60 playing by hand. In lieu, therefore, of employing a straight row of air channels in the tracker bar I provide a slightly irregular or waved or serpentine or other character of row of air channels so as to avoid the 65 absolute precision or mechanical accuracy in the sounding of the notes, and to, in lieu of such precision or mechanical accuracy, imitate the skill or hand habits of players 70 playing a piano by hand, the result being 75 that the rendition instead of producing a merely mechanical impression, which is recognized as an objection, will have the effect of providing that character of rendition produced by the hand.

The object of the invention is, therefore, to produce a tracker-bar for use in player pianos and in coöperation with a traveling music sheet which shall have an irregular line of air channels, the irregularity being 80 just sufficient to prevent mechanical accuracy in the striking of the notes, but on the contrary to imitate as far as possible in the rendition the slight irregularity or variation which is due to, even with very expert musicians, natural hand habit or the impossibility of the human to perform work 85 of this character with the same accuracy that follows the doing thereof by accurately made machine parts.

I illustrate my invention in the accompanying drawings, in which:

Figure 1 is a front view of a tracker bar of ordinary construction, with the exception that the row of air channels therein is not 95 on a straight line but on the contrary on an irregular or waved line, and

Fig. 2 is a vertical section through the same, on a larger scale, on the dotted line 2-2 of Fig. 1.

In the drawings 10 designates the tracker bar as a whole, and 11 the series of air channels therein, these channels, except for the irregularity in alignment thereof, being of usual character and connected with the 105 usual mechanism of a player piano, my invention residing more particularly in the arrangement of the air channels 11 on an irregular instead of a straight line.

The tracker bar 10 is shown as possessing 110 a single row of air channels 11, but it is well-known in the art that tracker bars

sometimes have a plurality of lines of air channels with proper slides for permitting the use of either line. My invention is equally applicable to tracker bars having 5 more than one line of air channels, and therefore is not limited to the single line of air channels illustrated in the drawings.

The line of air channels 11 is shown as waved along gentle curves, it being my purpose 10 that the line of air channels shall not be parallel with the longitudinal axis of the tracker bar, and this arrangement of the air channels is to secure in the rendition of a piece of music the impression of hand playing instead of the well-known mechanical sounds of player pianos. By reason of the waved or undulating nature of the line of air channels 11, at certain portions of the line, at the upper side thereof, are formed 15 what may be called apexes or high points, from which the adjacent or contiguous portions of the line diverge downwardly, and each of said diverging portions of the line contains a series of the air channels. In 20 other words in accordance with my invention I imitate the hand habits of performers on the piano and eliminate that mathematical precision of player pianos which results in the rendition being mechanical in sound. 25 I do not limit my invention to any specially defined line for the series of air channels, so long as said line in coöperation with the traveling perforated music sheet shall produce the slight irregularity in timing usual 30

in good hand playing. The line of air channels may be modified in direction at will, as long as the objective result is attained, and said line may be arranged to imitate the hand habit in piano playing of some special performer, if desired.

What I claim as my invention and desire to secure by Letters Patent, is:

1. A tracker-bar for player-pianos having the air channels therein arranged on an irregular line forming at intervals along the upper side of the line, at the high points thereof, apexes from which the adjacent portions of the line diverge downwardly, and each of said portions containing a series of the air channels.

2. A tracker-bar for player-pianos having the air channels therein arranged on a gently waved line, the adjoining portions of which each contain a series of the channels, for the purpose specified.

3. A tracker-bar for player-pianos having contiguous portions of its line of air channels disposed angularly to a horizontal longitudinal line through said bar, with a series of the perforations in each of said portions.

Signed at New York city, in the county of New York, and State of New York, this 27th day of January, A. D. 1915.

ARTHUR WARREN MACVEY.
